United States Patent Office

Des. 181,147
Patented Oct. 8, 1957

181,147

TEXTILE FABRIC OR SIMILAR ARTICLE

Karl Christian Hoffman, Rutherford, N. J., assignor to Aileen Mills Company, Biscoe, N. C., a corporation of Delaware

Application February 13, 1956, Serial No. 40,136

Term of patent 14 years

(Cl. D92—1)

I claim:

The ornamental design for a textile fabric or similar article, as shown.
